UNITED STATES PATENT OFFICE.

CHARLES O. YALE, OF ROME, NEW YORK.

SKATE.

SPECIFICATION forming part of Letters Patent No. 321,412, dated June 30, 1885.

Application filed January 3, 1885. (No model.)

To all whom it may concern:

Be it known that I, CHARLES O. YALE, of Rome, in the county of Oneida, in the State of New York, have invented new and useful Improvements in Roller-Skates, of which the following, taken in connection with the accompanying drawings, is a full, clear, and exact description.

This invention consists in a novel construction and combination of gripping devices connected to the foot-plate of the skate for the purpose of securely fastening the skate to boots or shoes of different sizes, all as herein-after more fully described, and specifically set forth in the claims.

The invention is fully illustrated in the annexed drawings, wherein Figure 1 is a side elevation of the rear portion of a skate provided with my invention. Fig. 2 is a top plan view of the same. Fig. 3 is a vertical transverse section taken on a line *x x* in Fig. 6. Fig. 4 is a vertical transverse section illustrating the operation of the gripping-jaws in engaging the sole of the boot or shoe. Figs. 5 and 7 are enlarged detail views illustrating the means for retaining the jaws in their engagement with the sole of the boot or shoe. Fig. 6 is an inverted plan view of the forward end of the foot-plate and attaching devices connected therewith.

Similar letters of reference indicate corresponding parts.

F represents the foot-plate of the skate. To the under side of the forward portion of said plate I adjustably secure two plates, *B B*, provided with transverse slots *r r*, through two of which the attaching-screws pass, a clamping-screw, *n*, passing through another of the slots, and, entering the foot-plate *F*, serves to retain said plate in its position. The plates *B B* project beyond the side edges of the foot-plate, and on the projecting portions of the plates *B B* are hinged the jaws *C C*, which are arranged to oscillate vertically toward and from the foot-plate. From said jaws project levers *l l* inwardly and upwardly sufficient to receive the downward pressure of the foot, and by said pressure automatically crowd the jaws *C C* into engagement with the edges of the sole of the boot or shoe, as represented in Fig. 4 of the drawings. By placing the fulcrums of

the jaws outside of the side edges of the foot-plate, the jaws are caused to press downward on the sole, and thus obtain a more secure hold thereon.

From the lower or pivoted ends of the jaws *C C* project inward secondary levers *l'*, and between the free end of said secondary levers and the plates *B B*, I employ suitable locking devices—such as keys or wedges *a*—for the purpose of retaining the jaws in their engagement with the sole of the boot or shoe. By means of springs *f*, secured to the plates *B B* and pressing against the ends of the keys or wedges, the latter are automatically forced into their engagement with the levers *l' l'*. The above-described jaw *C* and its levers *l* and *l'*, I form in one piece of metal, and thus impart to the respective members the requisite stability.

b b represent the usual lugs attached to the heel of the foot-plate *F*, for the purpose of engaging the heel of the boot or shoe, said plates being provided with inward projections *c c* for that purpose. In order to render said lugs adjustable in their position, I provide their base with slots *s s* for the reception of the screws *e e*, by which said lugs are clamped on the foot-plate, said slots allowing the lugs to be set in or out, according to the size of the heel of the boot or shoe to which the skate is to be fastened.

Between the central portion and heel portion of the foot-plate *I* adjustably secure a block, *d*, by means of a screw, *m*, passing through a longitudinal slot in the foot-plate and engaging the said block. The rear face of the block *d* is inclined, as shown in Fig. 1 of the drawings, for the purpose of crowding the heel back against the lugs *b b*, and thus cause the latter to obtain a firm hold on the heel.

Having described my invention, what I claim is—

1. The combination, with the foot-plate of a skate, of jaws pivoted at opposite edges of said plate, levers extending inward from said jaws to receive the downward pressure of the foot, keys or wedges for retaining the levers in their depressed position, and springs arranged to automatically force the keys or wedges into their engagement with the levers, substantially as described and shown.

2. The combination, with the foot-plate of a
skate, of plates secured thereon adjustable
laterally, jaws pivoted on said plates and ar-
ranged to engage the edges of the sole of the
5 boot or shoe, levers extending inward from
the jaws to receive the downward pressure of
the foot, keys or wedges for retaining the le-
vers in their depressed position, and springs
arranged to force the keys or wedges into their
10 engagement with the levers, all combined to
operate substantially as set forth and shown.
3. In combination with the foot-plate F and
key or wedge a, the vertically-oscillatory jaw
15 C, pivoted at its lower end, and the inward-
projecting lever l and secondary lever l', both
formed integral with the jaw, substantially as
described and shown.
4. In combination with the foot-plate F, the
20 plates B B, adjustably connected to the foot-
plate and projecting beyond the side edges
thereof, the jaws C C, pivoted on the project-
ing portions of the plate B B, and provided
with the inward-projecting upper levers, l l,
and with the supplemental lower levers, l' l',

and the keys a a, entering between the plates 25
B B and levers l' l', substantially as described
and shown.

5. In combination with the foot-plate F, the
plates B B, adjustably connected to said foot-
plate and projecting beyond the side edges 30
thereof, the jaws C C, pivoted on the project-
ing portions of the plates B B, and provided
with the inward-projecting upper levers, l l,
and the supplemental lower levers, l' l', the
keys a a, entering between the plates B B and 35
levers l' l', and the springs f f, pressing the
said keys into their said engagement, substan-
tially as described and shown.

In testimony whereof I have hereunto signed
my name and affixed my seal, in the presence 40
of two attesting witnesses, at Syracuse, in the
county of Onondaga, in the State of New York,
this 29th day of December, 1884.

CHARLES O. YALE. [L. S.]
